LIGHT ATTRACTING INSECT TRAP

Donald E. Gilbert, Box 2188, Jonesboro, Ark. 72401

Filed Apr. 14, 1975, Ser. No. 567,947

Term of patent 7 years

Int. Cl. D22—06

U.S. CL. D22—19

FIG. 1 is an isometric view looking obliquely at the top and two adjacent sidewalls of the insect trap;

FIG. 2 is an isometric view looking obliquely at the top and the two remaining sidewalls of the insect trap shown in FIG. 1, the bottom of the trap being plain;

FIG. 3 is a sectional plan view taken along line 3—3 in FIG. 1;

FIG. 4 is a longitudinal vertical sectional view taken along lines 4—4 in FIGS. 1 and 3;

FIG. 5 is a transverse vertical sectional view taken along lines 5—5 in FIGS. 1 and 3, and

FIG. 6 is an isometric view illustrating the ornamental wire-type guard sections mounted in the sidewalls of the trap.

I claim:

The ornamental design for a light attracting insect trap, substantially as shown and described.
